by William N. Low,

Attorney.

UNITED STATES PATENT OFFICE.

JOHN WALLACE, OF ALBANY, NEW YORK, ASSIGNOR OF ONE-HALF TO
GEORGE T. WEAVER, OF SAME PLACE.

BRASS FOR CAR-AXLE BEARINGS.

SPECIFICATION forming part of Letters Patent No. 292,452, dated January 22, 1884.

Application filed March 6, 1883. (No model.)

To all whom it may concern:

Be it known that I, JOHN WALLACE, of the city and county of Albany, in the State of New York, have invented certain new and useful Improvements in Brasses for Car-Axle Bearings, of which the following is a full, clear, and exact specification.

My invention relates to improvements in brasses for car-axle bearings and other journal-boxes that contain an anti-friction filling; and it consists in providing said brasses and boxes with a filling of compressed paper or paper-boards, as hereinafter set forth.

The object of my invention is to provide for car-axle and other bearings a cheap, effective, and durable anti-friction filling that will be readily renewable at slight cost. This object I attain by means of the construction illustrated in the accompanying drawings, which form part of this specification, and in which—

Figure 1 is a plan view of a car-axle brass containing my improvements; Fig. 2, a longitudinal section of the same; Fig. 3, a transverse section at the line X X; and Figs. 4 and 25 5 are respectively side and edge views of one of the paper filling-pieces.

As represented in the drawings, the brass A, which I preferably make of bronze, is in the form of a hollow shell or case, having one 30 of its ends made open, and provided with a detachable plate, a, which closes over the open end and completes the surrounding wall for the chamber that is formed in said brass for containing the anti-friction filling. The plate 35 a is secured in place by means of screw-bolts a', that are inserted in longitudinal bosses a'', which are formed at opposite sides of the chamber for containing the filling material and extend the full length of said chamber. The said 40 bosses are "undercut," as shown in Fig. 3, and form in effect a dovetail for securing the filling-pieces in place. The anti-friction filling is composed of the filling-pieces B, which are made of compressed paper or paper-board 45 that, while saturated with water or other suitable liquid, has been subjected to a pressure

of about eight thousand pounds to the square foot for the purpose of condensing and hardening it. The said filling-pieces are formed to fit transversely into the chamber of the brass A, and their ends are provided with the concave portions b, which fit around the bosses a'' so as to dovetail between them. The upper edges of said filling-pieces are made with a slight excess of material, as indicated by the space between the full and dotted curved lines in Fig. 4, so as to provide for the finishing of the filling to the required concavity after the pieces are secured in place. The filling-pieces B are inserted into the chamber of the brass A until the successive thicknesses fill the entire chamber, and then the closing-plate a is fixed in place to secure the said filling-pieces in said chamber. The brass is then placed under a revolving cutter, which finishes the filling to the required curvature.

With an equal quantity of lubricant, brasses provided with my filling will endure as much service, and run with as little, if not less, heating, as those that are filled with the best anti-friction metals, while the cost for filling and refilling them is but an insignificant sum in comparison with the cost of the metal fillings.

I claim as my invention—

1. An improvement in brasses for car-axles 75 and other bearings, the chambered shell A, containing a filling of compressed paper or paper-board, the said paper or paper-board being cut into shape, substantially as described, to form the filling-pieces B, which are 80 then fixed edgewise in the chamber of the shell A, as and for the purpose herein specified.

2. The combination, with the chambered shell A, provided with a detachable plate, a, 85 as herein described, of the filling-pieces B, composed of compressed paper or paper-board, as and for the purpose herein specified.

JOHN WALLACE.
